PANTS

Charles Avrich, Montreal, Quebec, Canada, assignor to Casual Togs, Inc., Montreal, Quebec, Canada

Filed July 24, 1972, Ser. No. 274,758

Term of patent 14 years

Int. Cl. D2—02

U.S. Cl. D2—28

FIG. 1 is a front perspective view of pants showing my new design;

FIG. 2 is a rear perspective view thereof;

FIG. 3 is a side elevational view;

FIG. 4 is a front elevational view;

FIG. 5 is an elevational view of the side opposite that shown in FIG. 3;

FIG. 6 is a rear elevational view;

FIG. 7 is a top plan view; and

FIG. 8 is a bottom edge view of one leg looking in the direction of the arrows VIII—VIII.

I claim:

The ornamental design for pants, as shown and described.
